ROAD SANDER

Peter Bogumill, Rib Lake, Wis.

Application January 26, 1937, Serial No. 122,394

5 Claims. (Cl. 221—145)

This invention relates to a sanding machine or a machine constructed and arranged to efficiently spread sand, salt or ashes or other material on icy roads, sidewalks or pavements. With modern traffic it is necessary to so distribute sand or other material when the streets or pavements are slippery and it is desirable to have some machine which will perform this operation quickly and efficiently.

10 It is an object of this invention therefore, to provide a very simple and efficient distributing device preferably carried on a vehicle which will distribute the material as desired over a certain area.

15 It is another object of the invention to provide such a distributing device comprising an elongated receptacle provided with agitating and discharging means, which discharge means may be adjusted as to the rate of discharge and it may have certain parts thereof rendered inoperative.

20 It is a further object of the invention to provide a simple and efficient discharging device which as stated, may be mounted upon a vehicle and which may be readily placed in or out of operation or adjusted as to the rate of discharge by the driver of said vehicle and from a point adjacent his driving position.

25 These and other objects and advantages of the invention will be fully set forth in the following description made in connection with the accompanying drawings in which like reference characters refer to similar parts throughout the several views and in which—

30 Fig. 1 is a view in side elevation of a vehicle such as a truck, showing the device mounted thereon;

35 Fig. 2 is a view in side elevation of the device, a portion being broken away and another portion being shown in vertical section;

40 Fig. 3 is a vertical section taken on line 3—3 of Fig. 2 as indicated by the arrows;

45 Fig. 4 is a horizontal section taken on line 4—4 of Fig. 3 as indicated by the arrow;

Fig. 5 is a partial plan view showing one of the 50 control plates used; and

Fig. 6 is a vertical section taken on line 6—6 of Fig. 5 as indicated by the arrows.

55 Referring to the drawings a device is shown comprising an elongated box or receptacle A which has a rectangular upper portion and has sides sloping toward its center with just enough inclination to have material move downwardly by gravity. The receptacle A is constructed and arranged to be mounted upon a vehicle B. Such vehicle may be of any suitable construction, pref-

erably of the truck type and such a vehicle is shown in Fig. 1 of which it will only be necessary to consider the frame members B1, the wheels B2 and the driver's cab B3 having the driver's seat B4 therein. This receptacle comprises end plates or frames 4 and 5. Plates 4 and 5 are mounted upon frame members B1. A side plate 6 extends between plates 4 and 5 and is bolted or connected thereto at its ends in any usual or suitable manner. Plate 6 extends from adjacent one upper corner of the end plates or frames downwardly to substantially the central bottom part of said end plates or frames. Another plate 7 extends between end plates 4 and 5 and is likewise connected thereto in any usual or suitable manner. Plate 7 also extends from adjacent one upper corner of the end plates 4 and 5 namely, the corner opposite that to which plate 6 extends, and plate 7 extends downwardly at an angle toward the lower end of plate 6. Plate 7, however, has its lower edge spaced some distance from the lower end of plate 6 and has secured thereto and extending longitudinally along its outer side and adjacent its lower edge a bar or narrow plate 8. Another plate 9 is provided which is hinged to plate 8 and thus to plate 7 by a plurality of hinges 10 which will be secured to plates 8 and 9. Plate 9 is arranged to be against plate 7 and extends downwardly toward the lower end of plate 6 and is disposed so that its lower end will engage the lower edge of plate 6 as shown in Fig. 3. A member 13 is secured to the outer side of plate 9 somewhat adjacent the lower edge thereof having formed therein a socket of general spherical form. A rod 12 has a ball at the end thereof received in the socket in member 13. Rod 12 passes through a block 11 and is provided with threads for some distance engaging threads in said block. Block 11 is swingingly mounted in a bracket 11a secured to a plate 4a fastened to end plate 4. Rod 12 comprises a universal joint at the outer end of its threaded portion comprising fork members 12b and 12c and having a block 12d disposed between the forks thereof and respectively connected to said fork members by the pins 12e. Rod 12 has a portion 12a extending from fork member 12b to a point adjacent the driver's seat B4 and which has a hand wheel 27 at its end. It will be seen that by turning the wheel 27 plate 9 can be moved toward or from plate 6. 50 Block 11 is swingingly mounted to prevent binding due to the fact that member 13 swings in an arc. A bar or plate 14 extends between and is secured to the end plates 4 and 5, the same being disposed adjacent the lower end of plate 6 at the 55

outer side thereof. A plurality of plates or slide members 15 are provided, the same extending throughout the length of plate 6, resting on member 14 and having their adjacent sides in contact, 5 which sides extend at right angles to the lower edge of plate 6. Plate 14 has secured therein headed and nutted bolts 17 which project through slots 15a in plates 15, which slots are of considerable length and extend parallel to the sides of 10 said plates. Springs 16 are secured at one end to the bolts 17 and at their other ends to plates 15 at the outer ends of the slots 15a therein. Bolts 17 are equipped with washers 17a below member 14 and above plates 15 respectively and 15 with nuts 17b. The plate 6 has its lower edge disposed substantially horizontally and the plates 15 are disposed so that they will move under this lower edge substantially in contact therewith. Springs 16 are under considerable tension and 20 tend to move the plates 15 inwardly against the lower edge of plate 9. Spring 16 are disposed for the most part within the slots 15a. Bolts 17 act as guides for the plates 15 as they move inwardly and the washers on bolts 17 are of a size to span 25 the slots 15a and be clamped down on top of plates 15 so as to hold the same stationary and prevent movement thereof by the springs 16.

The end plates 4 and 5 have secured thereto bearings or bearing boxes 18 in which is journaled a shaft 19 which extends lengthwise from plate 4 to plate 5 and between plates 6 and 9 and is thus disposed in the bottom of the receptacle formed by plates 4, 5, 6, 7 and 9. Shaft 18 has projecting therefrom throughout its length and 30 in circumferentially spaced relation pins 19a shown as of conical or pointed formation. Shaft 18 has rotatably mounted in the outer end thereof a pulley or sprocket 21 which will be arranged to be driven by a suitable belt or chain 22 from power furnished by a part of the vehicle on which 35 the device is mounted. Chain 22 may run over a sprocket B5 secured to a wheel of said vehicle. A clutch member 20 is also provided, the same being shown as having the two parts 20a and 20b and this clutch will be arranged to connect shaft 18 within the said receptacle to the sprocket 21. One part 20a of this clutch is secured to the side of sprocket 21 and has spaced laterally projecting teeth while the other part 20b is nonrotatably 40 but slidably secured to the projecting and reduced portion of shaft 19, the same having spaced laterally projecting teeth adapted to interengage with the teeth on part 20a. Suitable mechanism will be provided for operating clutch 20. This may include a bell crank lever 23 pivotally connected to a bracket 28 by a headed pivot 29. Bracket 28 will be secured to the outer side of plate 4. Lever 23 has one arm 23a comprising a clutch fork embracing part 20b and disposed in a 45 central groove therein. A rod 24 is pivotally connected to the other arm of lever 23 and extends to adjacent the driver's position in the vehicle B. Rod 24 could be pivotally connected intermediate the ends of a hand lever 25 pivotally mounted at its lower end at 26 in said vehicle.

With the described structure the sand, ashes, salt or other material to be distributed will be placed in the receptacle formed by plates 4, 5, 6, 7 and 9, the space within which is designated as 30. 50 When it is desired to discharge the material the driver or operator will turn wheel 27 and this will move rod 12 in the member 11 and swing the lower end of plate 9 the desired distance away from the plate 6. The driver will then push upon lever 75 25 to pull upon rod 24 and operate the clutch

member 20 to connect shaft 19 to sprocket 21, so that shaft 19 is rotated. This shaft with the pins 19a thereon will agitate and stir the material within the receptacle and break up any lumps therein. Shaft 19 with the pins 19a may also act as a feeder but is not necessary when fine loose material is delivered. The material will be thus discharged in the desired amount as the vehicle moves along and will be discharged onto the roadway, street or pavement. It will sometimes be desired that the material be not fed throughout the full length of the receptacle or of plates 9 and 6. The nuts on the bolts 17 holding certain of the slides 15 will be loosened and this will permit the springs 16 to move the plates 15 15 against the lower end of plate 9, these slides moving under the plate 6. Each slide that is so permitted to move will thus partly close the discharge opening and prevent any discharge from the receptacle throughout the width of said plate. 20 Thus the plates 15 throughout one end half of the receptacle could be loosened and the material discharged only through one-half of the length of plates 6 and 9. On the other hand, alternate plates 15 might be made to move and the 25 material would then be deposited in parallel streams or zones. The plates 15 will of course, move inward under the influence of springs 16 until they meet the edge of plate 9 no matter what distance it has been moved from plate 30 6. The plates 15 will be moved backward of course, should plate 9 be moved by operation of shaft 12.

From the above description it is seen that I have provided a simple and efficient structure of 35 distributing device and one which can be easily and quickly operated to discharge as desired by the driver of the vehicle on which the receptacle is mounted. If the material is fine and quite fluent it might not be necessary to operate the 40 shaft 18. By use of the plates 15 as described, the material can be distributed in the desired zones or areas. The receptacle comprising members 4, 5, 6 and 9 is constructed to have a large carrying capacity. The structure is easily made from 45 material which can be readily procured and can be made quite strong and rugged. It is obvious that the structure will have a high degree of utility for the purpose intended.

It will, of course, be understood that various 50 changes may be made in the form, details, arrangement and proportions of the parts, without departing from the scope of applicant's invention, which generally stated, consists in a device capable of carrying out the objects above 55 set forth, in the parts and combinations of parts disclosed and defined in the appended claims.

What is claimed is:

1. A distributing device for granular material adapted to be mounted on a vehicle having in 60 combination, a receptacle having downwardly converging walls, a plate adjacent the bottom of one of said walls swingable toward and from the other wall to engage the same or to be spaced therefrom to form a discharge opening, a second plate extending longitudinally of said other wall, a plurality of slidable plates arranged side by side on said last mentioned plate and movable beneath said other wall into engagement with said movable wall and across said discharge 65 opening to partially close the same, a spring connected to each of said plates urging the same to move toward said movable plate, means for holding each of said plates in stationary position whereby said discharge opening may be closed 70 75

throughout its length in zones each to the width of one of said slidable plates, said second plate having headed and nutted bolts extending vertically therein, said slidable plates each having an elongated slot therein extending in the direction of their movement in which one of said bolts is disposed, said springs being disposed largely in said slots respectively and the nuts in said bolts being adapted respectively to clamp said plates.

5 2. A distributing device having in combination, 10 a receptacle having downwardly converging walls, a plate at the lower portion of one wall movable away from and toward a position in contact with the other wall to form or close an opening between said walls, a series of adjacent 15 plates slidable under said other wall substantially in contact therewith toward said plate to abut said plate to close said opening and means for moving said plates into position to close said opening and for holding the same against such 20 movement.

3. A distributing device having in combination, 25 a receptacle having relatively movable walls adjacent its bottom to provide a variable discharge opening and a plurality of substantially horizontal plates arranged side by side adapted to selectively move beneath one of said walls in contact therewith and across said opening into abutting engagement with said other wall to close said opening for the width of each of said plates so 30 moved.

4. A distributing device adapted to be mounted 35 on a vehicle having in combination, a receptacle having downwardly converging walls arranged to have a discharge opening formed therebetween, a

plurality of plates arranged side by side throughout the length of said walls and adapted to move at right angles to the length of said walls beneath and substantially in contact with one of the same and into abutting contact with the other to close said discharge opening, resilient means connected to each of said plates for urging the same to move across said discharge opening and means for locking each of said plates in stationary position whereby zones of said discharge opening may be rendered inoperative, each having the width of one of said plates.

5. A distributing device for granular material adapted to be mounted on a vehicle having in combination, 15 a receptacle having downwardly converging walls, a plate adjacent the bottom of one of said walls swingable toward and from the other wall to engage the same or to be spaced the desired distance therefrom to form a discharge opening, a second plate extending longitudinally of said other wall having a substantially horizontal top surface, a plurality of slidable plates arranged side by side on said second plate and slid- 20 able thereon substantially horizontally beneath and in contact with said other wall to bring their ends into abutting engagement with said movable wall so as to extend across said discharge opening to close the same, a spring connected to each of said plates normally urging the same to move toward said movable plate and means for holding each of said plates in stationary position 25 whereby said discharge opening may be closed throughout its length in zones each equal to the width of one of said slidable plates.

PETER BOGUMILL.
